F. Ledermann
ATTORNEY

UNITED STATES PATENT OFFICE.

JOSEPH HEINZEL, OF WHITE PLAINS, NEW YORK.

OIL BURNER.

Application filed November 21, 1922. Serial No. 602,336.

To all whom it may concern:

Be it known that I, JOSEPH HEINZEL, citizen of the United States, and resident of White Plains, in the county of Westchester and State of New York, have invented certain new and useful Improvements in Oil Burners, of which the following is a specification.

This invention relates to oil heaters, the particular object being to design a heater which uses oil or other liquid as a fuel and is adapted to take the place of a coal fire in the ordinary furnace, thereby eliminating coal as a fuel, and has numerous advantages such as no stoking, no cleaning of ashes and carting of the same, and no other duties consequent to the use of coal, are required.

Another object is to provide a heater in which the oil flame is drawn up by and combines with a steam vapor which is generated by the flame, and is adapted to hasten atomization of the oil and increase the temperature of the flame.

Still another object is to provide in conjunction with the heater, float valve means similar to that of a carburetor, which at all times retains the fuel oil at a desired level, and, when failing to operate, automatically closes the fuel supply line.

These and other objects will become apparent in the description below, in which characters of reference refer to like-named parts in the drawings.

Referring briefly to the drawings, Figure 1 is a sectional elevational view of the heater and oil level control valve in operative position.

Figure 2 is a top plan view of the same.

Figure 3 is a sectional elevational view of a modified type of hood.

Describing the drawing in detail, the numeral 1 indicates a spherical bottomed pan which is mounted on legs 2. A number of uprights are formed on the periphery of the pan, and have horizontal arms 4 projecting outwardly intermediate of their length. Said arms are adapted to support an annular shell 5 upon which an inverted hood 6 is formed, the latter having an opening 7 at its upper end. Said shell is mounted above the pan, the space 8 between both the members being provided for air circulation into the area over the pan. A funnel 9 having a concavely formed wall 10 is mounted concentrically in the pan 1.

A water jacket 11 is supported above the

opening 7 of the hood and has a flat horizontal surface 12 which forms a heating iron for the water content of said jacket. The latter is supplied with water thru the pipe 13, and, as said contents are heated, the vapor rises to the head and is carried off thru the steam pipe 14. This steam lead courses downwardly to a position beneath the pan where it communicates with a condenser chamber 15. Said chamber has an upper pipe 16 and lower pipe 17 connected thereto which extend horizontally therefrom. The upper pipe has a nozzle or jet mounted on a valve 18 which is directly below said funnel. The nozzle of the valve extends upwardly and partly into the funnel. A relatively long stem 19 having a small hand wheel 20 at its end opens or closes said nozzle valve as desired. The lower pipe 17 as stated communicates with the lower end of the condenser chamber 15 and leads any of the condensed vapor out of the line thru the valve 21.

A fuel control valve which may be installed at any desired distance from the heater comprises an oblong casing 22 and has a sleeve 23 which projects downwardly within the chamber forming a guard for a stem 24 which has a hand wheel 25 at its upper end. A similar sleeve aligned with the aforesaid member 23 projects upwardly from the bottom of the casing, and has a tapered surface at its upper end which is adapted to seat the valve head 27, the latter being fixed to the lower end of the stem 24. A fuel delivery pipe 28 is connected to the lower end of the sleeve 26 and passes to the pan 1 at a level slightly below the upper edge of the latter.

An annular float 29 encircles the upper sleeve 23, and has a fulcrumed lever bar 30 rigidly attached thereto, the opposite end of the bar having a needle valve 31 mounted thereon which opens or closes the port 32 thru which the fuel oil passes from the main supply pipe 33. A shut off valve 34 is connected to the supply pipe 33 and has a lever 35 rotatably mounted thereon, said lever being adapted to close the valve when rotated to horizontal position. A wire 36 suspended from the end of the lever has a small bucket 37 at its lower end, said bucket being guarded within a housing 38. An overflow tube 39 connects the casing 22 with housing 38 and leads the excess oil from the casing into the bucket 37.

Figure 3 shows a modified type of water heater in which the water jacket comprises an elongated tank 40 which encircles the interior upper surface of the hood 6, the water being fed in thru the pipe 41 and out thru the pipe 42. This type of heater may be preferably used within a furnace and as stated does away with coal and its resultant attention. By removing the furnace grate 10 the pan may be slipped into place therein and allowed to stand on the floor, the legs 2 keeping the pan approximately on a level with the fire door.

The hood is then placed in position and 15 the water jacket 11 is filled. By opening the valve 34 the liquid will pass into the casing 22, and thru the pipe 28 to the pan 1, the level of the oil always being kept at the level shown, by the float 29. The surface of the oil in the pan is then ignited and 20 the flames and heat emanating therefrom will heat the water jacket 11. The steam which is released from the heated water passes thru the pipe 14 into the chamber 15. 25 As the pipe 14 is cold when the first volume of steam passes therethru, the latter will be condensed and may be led out of the line thru the lead 17. The steam which does not condense will pass into the pipe 16 and will 30 blow out thru the nozzle valve 18. As the steam rises thru the funnel in a strong draft it draws up and readily atomizes the burning oil.

The greater volume of vapor will be diffused over the surface of the oil in the 35 region about the funnel 9 because the draft is there at its maximum. Obviously, the intensity of the draft caused by the steam jet, will diminish in all radial directions toward 40 the periphery of the pan, and will be a minimum at said periphery. Consequently, the rate of vaporization of the oil will be highest about the funnel 9 and will be proportionately less at a distance from the funnel. 45 This is compensated for by the substantially spherical shape of the pan 1, the central portion having the greatest depth of liquid and the depth of oil at the edge of the pan being relatively shallow, thus permitting 50 the oil in the latter region to be more readily and rapidly heated.

I claim:

1. A heater using oil as a fuel and comprising an annular dished pan adapted to be flooded with oil, a concavely walled funnel passing concentrically thru said pan, a conical hood mounted over said pan, a water jacket above said hood, the water content being heated and changed to vapor 55 within the jacket by the burning oil, a steam

outlet pipe connected to said jacket having a nozzle valve at its opposite end, said valve when opened being adapted to pass said steam thru the funnel and over the pan, said steam being mixed with the oil flame to aid 65 atomization of the oil, and means for leading oil into said pan.

2. A heater using oil as a fuel and comprising an annular dished pan adapted to be flooded with oil, an upright funnel passing concentrically thru said pan and having its upper and lower openings of equal diameter and tapering inward to a reduced central throat, a hood mounted over said pan, 70 a water jacket above said hood, a steam outlet pipe connected to said jacket and having a nozzle valve at its opposite end, said valve when opened being adapted to pass said steam thru the funnel and over the pan, said steam being mixed with the oil flame to aid 75 atomization of the oil, and means for filling 80 said pan with oil.

3. A heater using oil as a fuel comprising an annular dished pan adapted to be flooded with oil, horizontal arms extending radially outward from the periphery of said pan, a conical hood, the latter being adapted to be supported by said arms above the pan and outside the periphery of the pan, a water jacket above said hood, a funnel in said pan, 85 a steam outlet pipe connected to said jacket and having a nozzle valve at its opposite end, said valve when opened being adapted to pass said steam thru the funnel and over the pan, said steam being mixed with the oil flame to aid 90 atomization of the oil, the heat from said burning oil being adapted to pass upwardly thru the hood and heat the contents of the jacket.

4. A heater using oil as a fuel and comprising an annular spherical surfaced pan, an upright funnel passing concentrically thru said pan, said pan adapted to receive fuel oil, the depth of said oil being greater in the region of the funnel, a hood mounted 100 over said pan, a water jacket above said hood, a steam outlet pipe connected to the jacket and having a nozzle valve at its opposite end, said nozzle valve communicating 105 with the funnel opening, said steam in passing upwardly from said nozzle being adapted to be diffused over the surface of the oil in the pan and aid in atomization of the oil, the oil at the pan being more rapidly heated 110 due to its lesser depth in that region.

Signed at New York, in the county of New York, and State of New York, this 18th day of November A. D. 1922.

JOSEPH HEINZEL.
